UNITED STATES PATENT OFFICE.

GARRY J. DORMANDY, OF LANSINGBURG, NEW YORK, ASSIGNOR TO THE UNITED SHIRT AND COLLAR COMPANY, A CORPORATION OF NEW YORK.

MACHINE FOR FOLDING COLLAR-BLANKS, &c.

SPECIFICATION forming part of Letters Patent No. 714,788, dated December 2, 1902.

Application filed January 15, 1901. Serial No. 43,336. (No model.)

To all whom it may concern:

Be it known that I, GARRY J. DORMANDY, a citizen of the United States, residing at the village of Lansingburg, county of Rensselaer, 5 and State of New York, have invented certain new and useful Improvements in Machines for Infolding the Edges of Blanks for Collars or Like Articles, of which the following is a specification.

10 My invention relates to machines for infolding the edges of blanks for collars or like articles.

More particularly, my invention relates to 15 that class of folding-machines in which an expanding and contracting templet or die is operated to rest upon the blanks to be infolded and folders or infolders actuated to move inwardly and outwardly for folding edge portions of the blanks over edge portions 20 of the templet.

25 My invention also relates more particularly to a new and useful construction of templet, whereby blanks of certain classes of shapes which cannot be infolded upon preceding machines may now be infolded, and to the construction of infolders to coöperate with such templet.

30 Heretofore in infolding-machines in which are employed upon the templet diagonally-moving corner-plates it has been impossible to secure the satisfactory infolding of certain forms of blanks—for example, such as have a projection, irregularity, or indentation at the side or end—because the templet-plates 35 could not be given such direction of movement as to properly withdraw both from the corner and from the projection or indentation. An object of my invention is to overcome this difficulty by providing an additional templet-plate corresponding to that portion of the blank containing the projection or indentation, the said additional plate fitted to move in a direction independent of the other plates and adapted to the proper 40 withdrawal from the projecting or reëntering part of the folded blank. Another advantage in the additional plate is the material reduction in the spaces between the expanded plates where it is not desired to have the 45 plates overlap.

50 Another object is to do away with the usual

diagonal slideways and slide-bars for the corner-plates, such devices being very complicated, and for this purpose I have provided transverse guides for the said additional or 55 side templet-plate, and by moving the corner-plates transversely from the same actuating means and simultaneously sliding the corner-plates longitudinally the diagonal movement thereof is effected. This allows a more simple 60 construction, which also is effective in maintaining in alinement the outer edges of the templet-plates.

I will first describe an infolding-machine embodying my invention and then point out 65 its novel features in the claims.

In the accompanying drawings, Figure 1 is a top view of an infolding-machine embodying my invention and adapted to infold edge portions of collar-blanks for a special form of 70 collar having a projection at one side, part of the templet-positioning mechanism being removed. Fig. 2 is a top view of the machine shown in Fig. 1, the parts in a different relation. Fig. 3 is a part vertical section taken 75 on the plane 3 3 of Fig. 2. Fig. 4 is a vertical section taken on the plane 4 4 of Fig. 2, the templet-positioning arm and templet shown in full and as somewhat elevated. Fig. 5 is an enlarged detail showing in top view 80 the templet of Figs. 1, 2, and 4, but in its contracted position. Fig. 6 is a top view of the same, the plates expanded. Fig. 7 is a bottom view of the same templet, its plates contracted, certain parts cut away to better 85 illustrate the construction; and Fig. 8 is a like bottom view of the templet with its plates expanded. Fig. 9 is a vertical section taken on the plane 9 9 of Fig. 8. Fig. 10 is a vertical section taken on the plane 10 10 of Fig. 7. 90 Figs. 11 and 12 are perspective detail views of parts of the templet. Fig. 13 is a bottom view of a modification of the templet of Fig. 1 for a blank having a different outline and in the infolding of which my invention may 95 be utilized. Figs. 14 and 15 illustrate forms of blanks that may be infolded by the use of the modification and the first-illustrated templet, respectively.

Similar letters of reference are employed to 100 designate corresponding parts.

A represents the bed of a machine embody-

ing my invention adapted to constitute a support for the blanks to be infolded. A chamber A' may be provided in the bed for the reception of a heating medium when desired.

5 B represents a templet adapted to be positioned upon and removed from the blanks upon the bed.

C represents diagonally-moving infolders fitted to move inwardly and outwardly to infold edge portions of the blanks over edge portions of the templet B. D represents other infolders.

The templet used in the machine illustrated in Figs. 1 to 12 (see Fig. 8) is when expanded of like form to the folded blank Z, Fig. 15, which is provided with the pointed projection z, and the infolders C and D are constructed to conform to the same blank and to the templet edges.

15 20 A convenient infolder-actuating means is that shown in my pending application, Serial No. 555,471, patented September 2, 1902, No. 708,030, and may be described as follows:

E represents angle-bars secured in the usual manner by bolts e upon the bed A, each pair of which constitutes a slideway or guide for a member F, to which an infolder C is attached, and the attaching means may be adjustable longitudinally of the blank, as 25 30 by the slot c, formed in the infolder, and a bolt c', passing through the slot and screwed into the slide F, where the latter projects beneath the infolder. A pin G, adjustably connected to the slide F through a longitudinally-sliding plate G', slot g in said plate, and bolt g', projects downwardly from said plate G' to engage a cam h, provided in a cam-plate H. The cam-plates H of the several infolders are 35 40 preferably arranged in the form of a ring and so connected that they may be moved simultaneously to and fro to operate the cams h to move inwardly and outwardly their respective infolders C.

I represents a ring that may be employed 45 50 to actuate the cam-plates H, which latter are attached to the ring through a concentric groove i in the ring in which the cam-plate is fitted and bolts i' passing through the cam-plates. The position of the cam-plates within the groove i may be altered, as should it be desired to alter the position of a slideway E. E. The ring I is fitted within an annular way a, formed in the bed A beneath the infolder slideways E.

55 I' represents a handle by which the ring I may be moved to and fro by hand.

With the form of blank illustrated I preferably employ four diagonally-moving or corner infolders C, each operating upon part 60 65 of one side and part of the adjacent end of the blank. The infolder D intermediate two of the infolders C upon one side of the blank is made to conform to the projection or indentation that is upon that side of the blank and is fitted to move inwardly and outwardly in a direction different from that of its ad-

jacent infolders, the direction depending on the projection or indentation of the blank and usually at right angles to the blank side. The infolder D may conveniently be actuated 70 from its adjacent corner-infolders through rollers d upon the infolder D, engaging slots formed in the ends d' of the infolders C and guided in its movements through a roller d', engaging a slot a' in the bed A of the machine. (See Figs. 2 and 3.) When the handle I' of the ring I is moved to and fro to move inwardly and outwardly in diagonal directions the infolders C, the infolders D will be actuated to move simultaneously inwardly and outwardly, the six infolders carrying all the edge portion of the blanks over edge portions of the templet B.

The templet B is provided with a bridge B', to which is attached the end of an arm 85 b, which is pivoted at a' to the bed A and is provided with a counterbalance b', acting to hold the templet normally elevated, the arm b, preferably made in two pieces, detachably or adjustably connected through bolts b'. 90 The mechanism described forms a convenient templet-positioning mechanism, securing the accurate placing of the templet upon the blanks upon the bed. Other suitable means are manifestly applicable.

95 I will now describe a construction of templet proper embodying my invention.

J represents a stock or body portion attached in suitable manner to the bridge B'.

Referring to Figs. 5 to 12, K K' represent 100 bottom slide-plates beneath the stock J and one on each side. These plates are fitted to move inwardly and outwardly in the following manner: In the top of the stock J are placed two slides k k, connected to the plate 105 K through holes at k² k² in the stock by means of screws k⁴ k⁴. Two other slides k' k' are connected to the bottom plate K' K' through openings at k³ k³ and screws k⁵ k⁵. One slide k and one slide k' is placed toward each end 110 of the stock, and for convenience the two slides k k' at each end may be fitted into the same transversely-arranged slideway at j³ in the stock J. At each end the stock J (see particularly Figs. 8 to 10) is cut away centrally to form a slideway for longitudinally moving slides L' L', to each of which is attached at the top a cam-plate L. For moving to and fro the cam-plates L there may be provided a wheel M, centrally pivoted upon 115 the stock J and provided with an operating-handle M' and with slots at m', through which connecting-rods m may be adjustably connected to the wheel. The two connecting-rods m are at their other ends pivotally connected at m² with the two cam-plates L L in such manner that when the wheel M is oscillated inward and outward movements of the cam-plates will be effected. In each cam-plate are provided at l l two oppositely-inclined 120 cam-grooves adapted to engage pins or rollers l' upon the slides k k', so that when the two

cam-plates are moved outwardly the bottom slide-plates K K' will be moved outwardly through the slides k k and k' k', to which they are connected. A reverse movement of 5 the handle M' will effect the drawing inward of the two plates K K'.

N N' represent side templet-plates screwed to the bottom plates K K', respectively, to move with the latter and provided with the 10 projecting portion or indentation n n', corresponding with the portion z of the blank Z.

O O' P P' represent corner templet-plates, making up, with the plates N N', when expanded the form of the blank to be infolded, 15 and each plate having edge portions adapted to rest directly upon the blanks upon the bed and to be withdrawn after the edge portions of the blanks have been infolded. The plates O O' P P' may be operated in the following 20 manner: The plates are moved lengthwise of the stock through the slide L', that moves longitudinally to and fro. (See Figs. 8 to 12.) The slide L' at each end is provided with transverse extensions Q Q', forming a guide 25 or slideway for transverse slides q q'. The plate O is attached to the transverse slide q, the plate O' to q'. A similar arrangement is employed at the other end of the templet as regards the plates P P'. When the slide L' is 30 moved inwardly and outwardly, it carries the templet-plates O O' with it, the slides q q', however, permitting a transverse movement. To control the transverse movements of the 35 corner templet-plates, I have shown the bottom plates K K' provided with extensions R R', projecting beyond and engaging the transverse slides q q', respectively. The extension R' is provided with an elongated depression or recess r' (see Fig. 12) to permit a 40 proper extent of longitudinal motion of the transverse slides, while the latter, as q', (see Fig. 11,) is provided with the short recess q'', by which the bottom plate K' as it moves inwardly and outwardly communicates a trans- 45 verse movement to the slide q', and consequently the corner-infolders O'. The illustration shows this mechanism to be the same for the four corner-infolders. By this construction a diagonal inward and outward 50 movement is imparted to the corner-infolders, the resultant of the simultaneous inward and outward movements of the slides L' and the bottom plates K K', all being controlled by the cam-plates L and by the wheel M.

55 In the modification of form shown in Figs. 13, 14 the same corner templet-plates O O' P P' may be retained and the side plates N N' changed for the plates N² N³, the whole then corresponding to the form of folded 60 blank Z, shown in Fig. 14, the depression or indentation z' corresponding with the parts n² n³ of the templet-plates N² N³.

Referring now more particularly to Figs. 1 and 4, I will describe a pressing mechanism 65 that may with convenience be employed in connection with the infolding mechanism de-

scribed. S represents any suitable form of table, above which the bed A is supported by castings S', resting on the table. A pressing-plate T is connected with pressers t, that are 70 located above infolders, by means of vertical bolts t' and nuts t'' thereon. U represents a cross-bar rigid with the plate T through the projections U', and u represents a spring or springs which press upward the cross-bar U 75 and presser-plate T. The pressing is accomplished through the pressers bearing downward upon the infolders, which are above the infolded blank edges. For this purpose a lever V is provided. The lever V is piv- 80 oted at v to the downwardly-projecting standard V', and it rests near its pivot upon the cross-bar U. The far end of the lever V is connected, through the bar or link w, with a treadle W, which may be operated by foot to 85 lower all the pressers t to press the blanks.

The operation of the foregoing mechanism may be as follows: In the initial position the infolders and templet-plates are moved outwardly and the templet and the pressers are 90 held elevated. A blank or blanks are first placed on the bed within the infolders, but extending over the edges thereof. The operator by the handle M' lowers the templet upon the blanks, operates the infolders by 95 throwing the handle I' to the left, contracts the templet by means of the lever M', throwing it to the left and allowing the templet to rise, operating the pressers by lowering the treadle W, releasing the treadle, and moving the infolders outward by the handle I', when the folded and pressed blank may be removed 100 from the bed.

As regards my new templet it may be used 105 in connection with any infolding means other than that described without departing from the invention. With some forms of blanks, for example, to which my invention could be applied the additional infolder D might be dispensed with. The infolders, moreover, 110 may when desirable, as when lock-corners are to be formed, be operated in series or succession within the principles illustrated in my pending application, Serial No. 735,544.

There are many practical forms of blanks 115 in the folding of which my invention will be of advantage other than the two illustrated, one example of which is the reversible link-cuff.

When desired, independent guiding means 120 may be employed for the corner templet- plates. In employing the term "diagonal" with reference to the corner plates or infolders I do not intend to limit myself to any particular angle of inclination; but while an angle of about forty-five degrees is usually pref- 125 erable any angle may be employed that will properly withdraw the plates or infolders from the folds both at the side and the end of the blank. When I speak of "transversely-moving plates," I mean that such plates pref- 130 erably move at nearly a right angle to the main outline of the blanks; but I wish to

cover all arrangements in which such plate is made to move in a different direction or curve from the corner-plates adjacent.

What I claim is—

- 5 1. In an infolding-machine for blanks for collars or like articles the combination of a support for the blanks to be infolded, infolders fitted to move inwardly and outwardly for infolding edge portions of the blanks, and a 70
10 templet adapted to bear upon the blanks upon said support and provided with diagonally-moving corner-plates, and a transversely-moving templet-plate corresponding to some irregularity, indentation or projection of the 75
15 blank to be folded and means for effecting inward and outward movements of said plates, whereby the templet edges may be withdrawn from the folded blank.
2. In an infolding-machine for blanks for 80 collars or like articles, the combination of a support for the blanks to be infolded, a templet, the said templet provided with corner-plates constructed and fitted to move inwardly and outwardly diagonally, a templet-plate intermediate in 85 location of two main corners of the blank, constructed and fitted to move inwardly and outwardly at an angle substantially different from the movements of the adjacent corner-plates, the said templet-plates having edge 90
95 portions adapted to bear directly upon the blanks upon said support and within edge portions of the blanks, and a part for effecting the inward and outward movements of the templet-plates; infolders constructed and fitted to move inwardly and outwardly whereby edge portions of the blanks upon said support may be infolded over edge portions of said templet, and means whereby the folds of the 100
105 blanks may be pressed between the support and infolders before the latter are moved outwardly, and after the templet-plates are withdrawn from the folds of the blanks.
3. In an infolding-machine for blanks for 110 collars or like articles, the combination of a support for the blanks to be infolded, a templet, the said templet having a generally rectangular form, and upon opposite edges thereof of three templet-plates at each edge, the corner-plates at each edge fitted to receive diagonal inward and outward movements, the 115
120 other plates fitted to move inwardly and outwardly transversely, a part for effecting the inward and outward movements of the six templet-plates, and infolders constructed and fitted to move inwardly and outwardly for infolding edge portions of the blanks over edge portions of the templet.
4. In an infolding-machine for blanks for 125 collars or like articles, the combination of a support for the blanks to be infolded, a templet, the said templet provided with corner-plates fitted to move inwardly and outwardly diagonally, a templet-plate intermediate in 130
135 location of two main corners of the blank, constructed and fitted to move inwardly and outwardly at an angle substantially different from the movements of the adjacent corner-plates, the said templet-plates having edge portions adapted to bear directly upon the blanks upon said support and within edge portions of the blanks, and a part for effect-

ing the inward and outward movements of the templet-plates; corner-infolders constructed and fitted to move inwardly and outwardly, an infolder corresponding to the said last-named templet-plate, fitted to move inwardly and outwardly at an angle substantially different from the movements of the adjacent corner-infolders, and means for effecting the inward and outward movements of infolders whereby edge portions of the blanks may be infolded over edge portions of the templet.

5. In an infolding-machine for blanks for 80 collars or like articles, the combination of a support for the blanks to be infolded, a templet, the said templet provided with corner-plates fitted to move inwardly and outwardly diagonally, a templet-plate intermediate in 85 location of two main corners of the blank, constructed and fitted to move inwardly and outwardly at an angle substantially different from the movements of the adjacent corner-plates, the said templet-plates having edge 90
95 portions adapted to bear directly upon the blanks upon said support and within edge portions of the blanks, and a part for effecting the inward and outward movements of the templet-plates; infolders constructed and fitted to move inwardly and outwardly whereby edge portions of the blanks upon said support may be infolded over edge portions of said templet, and means whereby the folds of the 100
105 blanks may be pressed between the support and infolders before the latter are moved outwardly, and after the templet-plates are withdrawn from the folds of the blanks.

6. A templet or die for infolding-machines comprising in combination a stock or body portion provided at one edge thereof and at each end of said edge, with a diagonally-moving corner templet-plate, and one or more transversely-moving templet-plates intermediate of said corner-plates, and a part 110 for effecting inward and outward movements of said templet-plates.

7. A templet or die for infolding-machines comprising in combination a stock or body portion provided at one edge thereof and at each end of said edge with a corner templet-plate, and a transversely-moving templet-plate intermediate of said corner templet-plates, a to-and-fro part for effecting the inward and outward movements of the intermediate templet-plate and longitudinal movements of the corner-plates, and means operated by the intermediate templet-plate for effecting movements of the corner-plates transversely to the longitudinal movements thereof, whereby diagonal movements are effected in the said corner-plates.

8. A templet or die for infolding-machines comprising in combination a stock or body portion provided with transversely-arranged 130
135 slideways, side templet-plates fitted to move inwardly and outwardly in said slideways, slides fitted to move inwardly and outwardly longitudinally, corner templet-plates, con-

nected to said slides to move longitudinally therewith, the said corner-plates fitted to said slides to move transversely thereon, means actuated by the said side templet-plates for effecting the transverse movements of said corner templet-plates, whereby a diagonal movement may be imparted to the latter, and a part for effecting the inward and outward movements of the side and corner templet-plates.

9. In a templet or die for infolding-machines, the means of producing a diagonal movement in a corner templet-plate, comprising in combination with such corner-plate and a side plate adjacent thereto, of

means for effecting outward and inward movements of said side plate, means for effecting similar movements lengthwise of the templet in said corner-plate, and means carried by said side plate upon which said corner-plate is fitted, whereby the corner-plate is maintained in alinement with said side plate.

In testimony whereof I have signed my name to this specification in the presence of 25 two subscribing witnesses.

GARRY J. DORMANDY.
